ATTORNEY

UNITED STATES PATENT OFFICE.

ZENO OSTENBERG, OF SAN JOSE, CALIFORNIA, ASSIGNOR TO THE CALTEX COMPANY, OF SAN JOSE, CALIFORNIA, A CORPORATION OF CALIFORNIA.

CENTRIFUGE.

Application filed August 31, 1921. Serial No. 497,306.

To all whom it may concern:

Be it known that I, ZENO OSTENBERG, a citizen of the United States, and resident of San Jose, in the county of Santa Clara and State of California, have invented certain new and useful Improvements in Centrifuge, of which the following is a specification.

This invention relates to that type of centrifuge used in the nitration of cotton for commercial purposes.

It is the object of this invention to provide a centrifuge of the character indicated that may be quickly and easily loaded and quickly and easily dumped and reset for loading without the great expense of time and labor necessitated by centrifugals as now constructed, and without the risk to life and property presented by their present form.

20 In the drawings,—

Figure 1 is a section taken vertically through my improved type of centrifuge.

Figure 2 is a plan view taken on line 2—2 of Figure 1.

25 Figure 3 is a section through the feed chutes taken on line 3—3 of Figure 1.

Figure 4 is a section through the hopper cover taken on line 4—4 of Figure 1.

30 Figure 5 is a section through the water inlet portion taken on line 5—5 of Figure 1.

Figure 6 is an illustration of another embodiment of my invention, part broken away.

Referring more particularly to the drawing, at 1 is shown a hopper with a discharge 35 outlet 2 and an annular water supply passage 3 formed by the inwardly turned upper edge 4 supplied by pipe 5.

Hopper 1 is provided with an exterior flange 6 resting on inner wall 7 of an annular chamber 8 having a discharge outlet at 9, the outer wall 10 of said channel extending upwardly and forming a seat for cover 11. Cover 11 is provided with an annular inwardly directed lip 12, and an outwardly extending flange 13 supporting a head 14, the latter being axially aligned with the hopper 1. In head 14 is formed central chute 15 and feed chutes 16—16^a, the central chute 15 broadening out above chutes 16—16^a to form a sleeve 17.

Axially arranged in hopper 1, chute 15 and sleeve 17 is a shaft 18 carrying a small annular bowl 19 having a flaring side 20 and a flange 21 extending outwardly from the upper edge of said side. Resting on flange

21 is a bowl top 22 preferably having a perforated flaring side 23 terminating in an outwardly extending flange 24 adapted to rest on flange 21, and a flaring apron 25. On top 22 are arranged a number of lugs 26 60 on each one of which is pivotally mounted a dog 27 moving in a vertical plane and weighted above its pivotal point and toward the top 22 as at 28. The dog 27 is provided with a hook 29 adapted to engage the under 65 surface of flange 21 but normally disengaged therefrom as shown in dotted lines at 30. Top 22 is provided with an opening 31 fitted with a receiving pipe 32 flaring at its upper end 33 to encompass the lower end of 70 chute 15 and adapted to engage lip 12 on cover 11.

At 34 is a member slidably mounted in sleeve 17 and having an arcuate inner and lower surface 35 upon which is arranged a 75 thrust bearing 36, the lower element 37 of which engages surface 35, and the upper element 38 of which is rigidly secured to the upper end of shaft 18. Element 38 is internally geared at 39 to engage gear 40 on 80 an element 41 mounted on driving shaft 42 operating in bearing 43. The ends of shafts 18 and 42 are curved as shown and contact with each other. Element 34 and parts carried thereby are raised and lowered by any 85 suitable means as lever 44 engaging flanges 45 on said element 34.

In applying the device to one specific use its operation is as follows, the bowl 19 being empty and in the position indicated in 90 dotted lines.

By operating lever 44 the bowl 19 is brought up into engagement with top 22 and the whole raised so as to be suspended freely from element 37 as shown in solid 95 lines. Power being applied to shaft 42 the shaft 18 and parts carried thereby are rotated at the required speed, the centrifugal force generated throwing dogs 27 into engagement with flange 21 and securely locking the bowl 19 and top 22 together. Nitrated cotton being fed in a given quantity through chutes 16—16^a—15 it falls into bowl 19 and is thrown outwardly therein by the centrifugal force generated by the revolving 100 parts and assumes a position as indicated in dotted lines at 46.

During the spinning of the bowl the excess acids in the nitrated cotton are thrown out through the perforated side 23 of top 22 110

against cover 11 and collected in channel 8 to be carried away through pipe 9.

When the nitrated cotton is sufficiently wrung the device is stopped and shaft 18 lowered, the dogs 27 automatically disengaging themselves from flange 21 so that the bowl 19 may be lowered to the position shown in dotted lines, the top 22 resting on hopper 1 as shown. The bowl is now spun 10 again by applying power to shaft 18 thereby throwing all of the material therein outwardly against the walls of hopper 1, where it is taken up by the water flowing thereover from passage 3 and carried away through 15 the discharge 2.

A moment's revolving of bowl 19 having thoroughly cleaned it it is again raised and filled and the process repeated.

In a centrifuge constructed and operated 20 as above set forth the filling is effected in a short space of time; excess liquid is quickly and effectively removed into a suitable collecting chamber; after wringing, the centrifuge bowl is automatically unlocked, 25 opened and emptied into a separate collecting chamber; the said bowl is quickly and easily reassembled and automatically locked preparatory to refilling.

By connecting and mounting the shafts 30 18 and 42 as shown a positive drive is effected between the two shafts and yet the lower shaft has the necessary flexibility.

Under certain conditions it may be desirable to support bowl 19 from below instead of from above and this can be accomplished without any complexity of parts as shown in Figure 6 of the drawings.

It is to be understood, of course, that while I have herein shown and described 35 0 one particular embodiment of my invention, changes in form and construction may be made within the scope of the appended claims.

I claim:

1. In a centrifuge, a hopper, a conduit 45 entering the upper portion thereof and encircling the same and provided with a discharge passage to said hopper, an acid chamber encompassing the upper portion of said 50 hopper, and drainage means for said chamber.

2. In a centrifuge, a hopper, an acid collecting chamber encompassing the upper portion thereof, a bowl revolvably and concentrically arranged in said chamber and movable along the axis thereof, a cover for 55 said bowl, means for locking said bowl and cover when in engagement, and means for supporting said cover on said hopper when 60 the bowl is disengaged therefrom.

3. In a centrifuge, a hopper, an acid collecting chamber encompassing the upper portion thereof and communicating therewith, a bowl revolvably and concentrically 65 arranged in said chamber and movable

along the axis thereof, a cover for said bowl arranged to engage the same when in a raised position, and means for closing the communication between the hopper and acid chamber when said bowl is disengaged from 70 said cover and lowered a distance therefrom.

4. In a centrifuge, a hopper, a conduit entering the upper portion thereof and encircling the same and provided with a discharge passage to said hopper, an acid chamber encompassing the upper portion of said hopper, and drainage means for said chamber, a bowl concentrically and revolvably mounted in said hopper and chamber and discharging into said chamber, a cover member 75 arranged on said bowl, and a feeding tube concentrically arranged upon said cover member.

5. In a centrifuge, a hopper, an acid collecting chamber encompassing the upper portion thereof, a bowl revolvably and concentrically arranged in said chamber and movable along the axis thereof, a cover for said bowl, means for locking said bowl and cover when in engagement, and means for supporting said 80 cover on said hopper when the bowl is disengaged therefrom, an inwardly extending flange carried by said acid chamber, a feeding tube concentrically arranged upon said cover and having an outwardly flaring 85 upper edge adapted to engage said flange.

6. In a centrifuge, a bowl, a cover therefor, a driving shaft axially mounted on said bowl, said bowl and shaft being shiftable as a unit along the axis thereof, means for shifting said bowl and shaft in either direction along said axis, and means for effecting the separation of said bowl and cover when 90 said bowl is shifted in one direction and means for supporting said cover on said hopper when the bowl is shifted in the opposite direction.

7. In a centrifuge, a bowl, a cover therefor, a driving shaft axially mounted on said bowl, said bowl and shaft being shiftable 100 as a unit along the axis thereof, means for shifting said bowl and shaft in either direction along said axis, and means for effecting the separation of said bowl and cover when said bowl is shifted in one direction and means for effecting the registration of said bowl and cover when said bowl is shifted in the opposite direction.

7. In a centrifuge, a bowl, a cover therefor, a driving shaft axially mounted on said bowl, said bowl and shaft being shiftable 110 as a unit along the axis thereof, means for shifting said bowl and shaft in either direction along said axis, and means for effecting the separation of said bowl and cover when said bowl is shifted in one direction and means for effecting the registration of said bowl and cover when said bowl is shifted in the opposite direction, said shaft having a joint formed therein below said shifting means to permit a swinging movement of 115 said bowl and the lower portion of said shaft.

8. A centrifuge including a hopper, an acid chamber arranged thereon, a head supported on said acid chamber, a sleeve carried by said head, a member having a curvilinear surface in one end thereof slidably mounted in said sleeve, means for adjusting said member in said sleeve, a two part shaft having curvilinear and engaging ends, a roller 120

bearing support for one part of said shaft and engaging the curvilinear surface of said member, a gear carried by said part, a gear carried by the other part of said shaft and 5 loosely engaging the gear carried by the said first mentioned part, and a bowl carried by said shaft and arranged in said hopper and chamber.

9. A centrifuge including a hopper, a conduit entering the upper portion thereof and 10 encircling the same and provided with a discharge passage to said hopper, a bowl revolubly and concentrically mounted with relation to said hopper and movable along 15 the axis thereof, a cover normally carried by said bowl, and means for supporting the cover on said hopper when said bowl is moved along its axis away from said cover.

10. A centrifuge including a hopper, a conduit entering the upper portion thereof and 20 encircling the same and provided with a discharge passage to said hopper, a bowl revolubly and concentrically mounted with relation to said hopper and movable along 25 the axis thereof, a cover normally carried by said bowl, and an outwardly extending flange carried by said cover and engageable with the upper portion of said hopper when 30 said bowl is moved along its axis away from said cover.

11. A centrifuge including a hopper, a conduit entering the upper portion thereof and 35 encircling the same and provided with a discharge passage to said hopper, a bowl revolubly and concentrically mounted with relation to said hopper and movable along 40 the axis thereof, a cover normally carried by said bowl, means for supporting the cover on said hopper when said bowl is moved along its axis away from said cover, and 45 means for introducing material into said bowl through said cover.

12. A centrifuge including a hopper, means for introducing liquid into said 45 hopper around the upper edge thereof, a bowl revolubly and concentrically mounted with relation to said hopper and movable

along the axis thereof, a cover normally carried by said bowl, and means for supporting the cover on said hopper when said 50 bowl is moved along its axis away from said cover.

13. In a centrifuge, a hopper, means for introducing liquid into said hopper around the upper edge thereof, an acid chamber 55 encompassing said hopper and extending below the upper edge thereof, and drainage means for said chamber.

14. In a centrifuge, an acid chamber having an upturned inner wall to form an acid 60 collecting channel, a hopper mounted on said wall and extending thereabove, and a bowl revolubly mounted in said hopper and chamber and movable along its axis from a point where its upper edge is above the 65 upper edge of said hopper to a point where its upper edge is below the upper edge of said hopper.

15. A centrifuge, a bowl, a cover therefor, a driving shaft axially mounted on said 70 bowl, said bowl and shaft being shiftable as a unit along the axis thereof, means for shifting said bowl and shaft in either direction along said axis, and means for effecting the separation of said bowl and cover 75 when said bowl is shifted in one direction and means for effecting the registration of said bowl and cover when said bowl is shifted in the opposite direction, an acid chamber 80 encompassing said hopper, a head carried by said acid chamber, a feed tube carried by said bowl cover, and a feed tube extending through said head and discharging into said first mentioned feed tube.

16. In a centrifuge, a hopper, an acid collecting chamber encompassing the upper portion thereof, an imperforated bowl revolubly and concentrically arranged in said chamber and movable along the axis thereof, a perforated cover for said bowl and 90 means for introducing material into said bowl.

ZENO OSTENBERG.
